WINDOW

Volono Hopi Blauntia and Noah Clinton Lewis,
Tulsa, Okla.

Application February 9, 1935, Serial No. 5,776

3 Claims. (Cl. 189—66)

This invention relates generally to improvements in windows for dwellings and the like and the main object is to provide a window and sash assembly constructed and arranged in novel fashion so that the sashes though slidably mounted for their usual opening and closing action may also be swung inward when access to the outer sides is necessary for washing the glass.

Another and important object is to provide an assembly of this kind in which the sashes are each made up of three nested sections or frames, the outer one of which serves as a guide and carrier for the whole and the two inner ones of which are hinged thereto and carry the glass between them the inner one being further removable for convenient replacement of the glass.

Another object is to provide a window assembly including a frame in which the sashes are slidably mounted, each sash having a gear toothed rack or racks with which a connecting gear wheel or wheels is meshed so that each sash counterbalances the other, there being means, however, for disengaging the gear wheel to permit independent movement of the sashes when desirable.

A further object is to provide an assembly of this kind including novel means for receiving and holding storm sash or screens in such manner that they may be put in place and removed from the interior of the frame.

A further object is to provide a novel fastening and supporting means for the several sections of the sashes.

With these and other objects in view as may appear in the course of the following specification, attention is directed to the accompanying drawings as forming a part thereof and as showing one practical embodiment of the invention.

In the drawings:

Figure 1 is an inside elevation of the window with the upper and lower sash respectively lowered and raised.

Figure 2 is an edge or side view of the window.

Figure 3 is an enlarged section along the line 3—3 in Figure 2.

Figure 4 is an enlarged horizontal section along the line 4—4 in Figure 1.

Figure 5 is a fragmental exterior elevation showing the screen mounting means and a screen in broken lines.

Figure 6 is a fragmental inside elevation of the lower portion of one sash showing the hinge rod for the inner sections thereof.

Figure 7 is an enlarged vertical section through one of the sash showing the swinging action of

the inner sash sections and showing in broken lines the innermost section removed.

Figure 8 is an enlarged fragmental inside side elevation of the window frame showing the ser-

rations for holding the sash in adjusted position.

Figure 9 is an enlarged elevation of one of the

locking devices for holding the sash sections to-

gether.

Referring now with more particularity to the drawings the window frame is designated gen-

erally at 1 and is of the usual rectangular open shape and form but is preferably made up or pressed from sheet metal and comprising sides 2, bottom or sill 3 and top or head 4. In cross sec-

tion the frame is generally of U-shape as shown in Figure 4 with the legs or spaced side webs 5 turned outward providing an exterior surround-

ing recess 6 to receive the dwelling wall (not shown) and with narrow out-turned lips 7 around the outer edges as a means for mounting the inner and outer facings, strips or architraves 8 and 9 which have crimps 10 to receive and en-

gage said lips. Inwardly of the frame 1 these facings 8 and 9 have beads or folds 11 and 12 the outer ones 12 being considerably wider than the inner ones 11 for a purpose to be described. A stop 13 is provided centrally along the flat inner face of the frame entirely around the sides 2, bottom 3 and top 4 and is formed by an inwardly turned fold or crimp in the metal as shown.

Upper and lower sashes 14 and 15 are provided and each comprises three nested sections includ-

ing a rectangular outer carrier section 16, a smaller nested center section 17, and a still smaller and nested inner section 18. All these sections are of L or right angled cross section (Figure 4) and are nested so that the inner sec-

tions fall entirely within the confines or valley in the outer section with a space or cleft 19 in-

tervening between the inwardly turned webs of the center and inner sections to receive the glass window panes 20 and 21. Rattling of the panes is prevented by rubber or felt moldings 22 sur-

rounding the margins of the panes. The various sections 16, 17 and 18 are all set in the window frame 1 with one web of each outer section turned flat against and slidably engaging the sides 2 of the frame and with the other webs turned inwardly with the valleys formed between the webs turned toward the inner side of the

window and house. The outer sections 16 at the bottom are cut away leaving only a vertical web designated at 23 in Figure 7 and a hinge rod 24 is passed across the thus open end of each sash inwardly of the webs 23 and is welded or other-

wise secured at its ends to the sides of the sash. The center sash sections 17 then have a flange 25 turned downwardly at their inner margins hiding these hinge rods, and apertured hinge ears 26 are formed at the ends of this flange and at the sides of the sash and are pivotally mounted on the hinge rods 24 whereby the said center sash sections may be swung downward and inward from their nested position in the outer sections 16 as shown in Figure 7. The upper and lower sash 14 and 15 thus formed are slidably mounted in the frame of course on opposite sides of the stop 13. Rings 57 may be provided at the top of each inner section 18 as a convenience in pulling down the glass carrying portions of the sash.

Normally all three sections 16, 17 and 18 of each sash are held tightly in engaged and nested position by latch pins or bolts 27 (Figures 4 and 20 9) which are arranged at each side and near the top of each sash. These pins 27 are slidably and rotatably mounted through tubular necks or collars 28 welded or suitably secured to the inner sides of the inner sash sections and through registering apertures pierced through the sides of the center and outer sections 17 and 18 as shown at 29. The outer ends of the pins 27 are chisel pointed as shown at 30 and are adapted in the locked positions of the pins to engage vertical 25 rows or strips of serrations 31 on the inner faces of the frame sides 2 to frictionally lock the sashes in adjusted positions in the frame and to prevent rattling of the sash. The pins 27 have radially extending studs 32 which play in a slot 33 extended longitudinally along the collars 28 and which have three spaced circumferentially projected notches 34. When the pins 27 are in their outermost positions as described above the studs 32 rest in the outermost notches 34. Then by 30 partially rotating the pins 27 and pulling inward by the knobs 35 the pins may be disengaged from the apertures in the outer sash section 16 freeing the center and inner sections 17 and 18 so that they may be swung inward as described. 35 Then the pins 27 may be pulled further inward disengaging them from the center sections 17 so that the inner sections 18 may be removed for replacing the glass panes 20 or other operations. In either of the two last mentioned positions of 40 the pins 27 they may be locked by turning the studs 32 into appropriate notches 34 as will be readily understood. A small lock pin 35 is placed in aligned apertures 36 in the center and inner sections 17 and 18 of each sash and may be 45 removed when the inner section is to be removed.

It is thought that the operation of the sash will be understood from the foregoing. Since the center and inner sections of the sash may be swung inward the glass panes may of course be 50 readily washed or cleaned from within the house. The narrow inner beads 11 and stops 13 permit this inward swinging of the sash sections since they lie substantially flush with the outer webs of the outer sections 16 (Figure 4) while the 55 wider outer beads 12 hereinbefore described prevent outward swinging of the sash and form a water and weather proof joint.

The sashes 14 and 15 have gear toothed racks 37 and 38 secured vertically to each side and slidably extended through vertical slots 39 extended the length of the sides 2 of the frame as shown in Figure 2, these racks being secured in place by screws 40 (Figure 4) and have their toothed edges 41 turned inwardly toward each other and 75 spaced outwardly from the sides 2 as shown.

Gear mounting studs 42 are welded or otherwise suitably secured at 43 to the sides 2 at a vertically medial point thereof and extended horizontally outward therefrom between the racks 37 and 38. Gears 44 and 45 are slidably and rotatably mounted on these studs 42 and have elongated outwardly extended hub sleeves 46 provided with peripheral grooves 47. Operating shafts 48 and 49 are journaled horizontally and inwardly through the side facings 9 and the inner and outer side webs 5 above the gear hub sleeves 46 and have rigidly mounted shifting forks 50 engaging the grooves 47 in said sleeves. Knobs 51 are secured to the inner ends of the shafts 48 and 49 as a means for turning same. When the 15 gears 44 and 45 are properly meshed with the racks 37 and 38 the upper and lower sash are connected and while they may move freely upward and downward each sash counterbalances the other and they will remain in any adjusted 20 position in the frame. It is sometimes necessary (as for instance in cleaning the windows) that the sash move independently and this may be done by turning the knobs 51 which swing the forks 50 and pull the gears 44 and 45 out from 25 between and in mesh with the racks 37 and 38 as will be understood and which disconnects the sash. Reverse movement of the knobs of course reengages the gears with the racks.

Near the lower end of the frame 1 and on the 30 outer side thereof a seat 52 is formed for a screen or storm sash 53 and this seat is formed by turning out flanges 54 from the outer facings 9 in lieu of forming the beads 12 at these points, these flanges having inwardly turned lips 55 as shown. Above the flanges 54 the beads 12 are cut away at 35 56 flush with the sides of the frame 1. The screen or storm sash 53 which may be of any suitable form and which is of such width as to slip between the frame sides 2 is then passed end- 40 wise through the space provided by the openings or notches 56 and is then manipulated to come to rest at its lower end within the flanges 54 which hold it in place outside the window. This whole operation is readily performed from within the 45 window.

While we have herein set forth a certain preferred embodiment of our invention, it is understood that we may vary from the same in minor structural details, so as best to construct a practical device for the purpose intended, not departing from the spirit of the invention and within the scope of the appended claims.

We claim:

1. In a latch assembly for a window sash 55 assembly which includes a frame, the same having rows of serrations, an outer sash section slidably in the frame, a center sash section hinged in the outer section, and an inner sash section nested in the center section, and all of the said sections 60 having aligned apertures in alignment with the serrations on the frame, tubular necks extended inwardly from the inner sash section in alignment with the said aperture, the said necks each having a longitudinally extended slot through its 65 wall and notches extended laterally from the slot, lock pins slidably mounted through the said necks and each having a stud radially extended and slidably mounted through the said slot in the neck whereby the pin when its stud is moved into 70 the notch nearest the sash members will hold all the members together and will simultaneously engage the serrations on the frame to hold the sash assembly rigid therein, and whereby the pin as it is moved to place its stud in the other notches 75

will successively free the center and inner sash section from the outer and the inner section from the center.

5. 2. A window sash made up of three sections comprising outer, center and inner sections arranged in nested relation one within the other, all the sections being of right angled cross section and the center and inner sections being spaced apart to provide a mounting for the window glass, the said outer section having one web cut away at its lower side, a hinge rod extended across the sash at the lower cut away end of the outer section, ears turned downwardly from the said center section at its lower corners and pivotally mounted on the said hinge rod, and a flange turned down from the lower edge of the center sash section concealing the said hinge rod.

10. 3. A window sash made up of three sections

comprising outer, center and inner sections arranged in nested relation one within the other, all the sections being of right angled cross section and the center and inner sections being spaced apart to provide a mounting for the window glass, the said outer section having one web cut away at its lower side, a hinge rod extended across the sash at the lower cut away end of the outer section, ears turned downwardly from the said center section at its lower corners and pivotally mounted on the said hinge rod, and a flange turned down from the lower edge of the center sash section concealing the said hinge rod, means for releasably securing the sash sections together, and additional means for securing only the inner section

15. 5. 10. 15.
